United States Patent Office.

THOMAS DOLAN, OF PHILADELPHIA, PENNSYLVANIA.

Design No. 3,107, dated July 14, 1868.

DESIGN FOR A STOCKING-FABRIC.

The Schedule referred to in these Letters Patent and making part of the same.

TO ALL WHOM IT MAY CONCERN:

Be it known that I, THOMAS DOLAN, of the city and county of Philadelphia, State of Pennsylvania, have invented or produced a new and original Design for a Stocking-Fabric; and I do hereby declare that the accompanying drawing, and the following explanation thereof, form a full, clear, and exact description of the said design.

The figure in the accompanying drawing represents sufficient of a knitted fabric to illustrate my design.

In the body A of the fabric are parallel rows of diamond-shaped spots, *a*, and on each side of each of these rows is a row of similarly-shaped spots, *b*, and on the outer end of each of the latter spots is a diamond-shaped dot, *c*.

Intervening between the patterns thus formed is the zigzag tracery or net-work clearly represented in the drawing.

The spots *b* should differ in shade or color from the spots *a* and *c*, and all should differ in shade or color from the body of the fabric.

Without confining myself, however, to any specific shades or colors—

I claim the design for a stocking-fabric, substantially as herein described, and represented in and by the accompanying drawing.

In testimony whereof, I have signed my name to this specification in the presence of two subscribing witnesses.

THOMAS DOLAN.
